UNITED STATES PATENT OFFICE

DERVEN T. RYGYMYR, OF FOREST CITY, IOWA

SAFETY RAZOR

Application filed May 2, 1930. Serial No. 449,246.

The present invention relates to safety razors and more particularly to that type of safety razor in which the razor embodies means for guiding the strop, by means of which the blade of the razor is stropped and for oscillating the blade to bring alternate faces thereof into engagement with the strop.

The object of the invention is to provide a razor of this nature which is simple in construction, inexpensive to manufacture, thoroughly efficient and reliable and useful in operation, easy to manipulate and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a perspective view showing the razor in a released position,

Figure 2 is a longitudinal sectional view through the razor showing the blade in locked position,

Figure 3 is a perspective view thereof,

Figure 4 is a longitudinal section showing the blades in released position with strops in operative association therewith, and

Figure 5 is a detail view of the strop.

Referring to the drawings in detail it will be seen that the numeral 5 denotes a base plate of a razor head which includes the side 6 extending perpendicularly therefrom and being somewhat triangular in formation. A handle 7 projects perpendicularly from the base plate 5. In the outer upper corners of the sides 6 there is rockably mounted a blade 8 having a cog 9 connected therewith and in mesh with a cog 10 on the end of a shaft 11 in close proximity to the blade 8 so that a strop may be drawn between the roller shaft 11 and the blade and thus when the razor is

reciprocated back and forth along the strop the blade oscillates to prevent the proper face to the strop as will be well recognized to those skilled in this art.

A roller 12 is mounted in the lower corners of the sides 6 so as to hold the strop in proper position for engagement with the blade adjacent its cutting edge.

A bar 14 is rockably mounted as at 15 on one side 6 and has its snap connection with the other side 6. The central portion of the bar is projected as at 17 to engage the blade and hold it firmly against the roller 12 as is shown in Figure 2 for shaving purposes.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It is apparent that changes in the details of construction, and in the combination and arrangement of parts may be resorted to without departing from the spirit or scope of the invention as hereinafter claimed or sacrificing any of its advantages.

Having thus described my invention, what I claim as new is:

A safety razor of the class described comprising a head consisting of triangular shaped end parts and a bar connecting the side edges of the base portions of the triangular end portions together, a handle connected with the central part of the bar, a blade having trunnions at its ends journalled in the outer corners of the base parts of the triangular shaped ends, a roller journalled in the apexes of said ends, a holder bar for holding the blade against said roller, whereby said roller

acts as a guard for the cutting edge of the blade when the razor is being used for shaving, a second roller journaled in the ends of the head and spaced inwardly from the pivoted edge of the blade and gears connected with the trunnions of the blade and said second roller and meshing with each other for imparting a rocking movement to the blade when a strop is passed over the rollers.

10 In testimony whereof I affix my signature.

DERVEN T. RYGMYR.
